UNITED STATES PATENT OFFICE

EDWARD F. TERRY, JR., OF DENVER, COLORADO, ASSIGNOR, BY MESNE ASSIGNMENTS, TO THE GARDNER-DENVER COMPANY, OF QUINCY, ILLINOIS, A CORPORATION OF DELAWARE

AUTOMATIC VALVE FOR FLUID-OPERATED TOOLS

Application filed February 12, 1927. Serial No. 167,764.

The present invention relates to automatic valves for pneumatic and similar tools, and is in the nature of an improvement on the structure shown in my earlier Patent Number 1,728,312, granted September 17, 1929.

The object is to provide a novel valve that is exceedingly quick and effective in action, thus making it peculiarly useful with high speed tools.

In the accompanying drawings:

Figure 1 is a longitudinal sectional view through a tool equipped with the preferred embodiment of the invention and showing the working piston receiving air for its return stroke,

Figure 2 is a longitudinal sectional view showing the piston at the rear end of its stroke and in a position to receive air for the forward stroke,

Figure 3 is a detail perspective view of the valve.

In the embodiment disclosed, a cylinder 4 is illustrated, containing a piston chamber 5, in which a reciprocatory piston 6 operates, this piston having a hammer extension 7 on one side of the cylinder 4, and preferably integral therewith is located a valve casing 8 having spaced head chambers 9 and 10 connected by a reduced bore 11.

The outer end of the head chamber 9 is provided with an annular channel 12 that communicates with the rear end of the piston chamber 5 through a straight short passageway or port 13. The inner end of the head chamber 9 has communication with an intermediate portion of the piston chamber by a straight port 14. Between the ports 13 and 14, the head chamber 9 has an internal channel 15, from which opens an exhaust outlet 16 to atmosphere. The head chamber 10 is somewhat longer than the head chamber 9 and of less diameter. It is provided at its front end with an annular channel 17 that communicates by means of a short port 18 with the front end of the piston chamber 5 in advance of the piston 6. The rear end of the head chamber 10 has a straight port connection 19 with an intermediate portion of the piston chamber 5 in advance of the port 14. Between the

ports 18 and 19 there is formed in the head chamber 10 an annular channel 20, with which an exhaust port 21 communicates, said exhaust port being between the ports 18 and 19. Between the ports 19 and 21 there is formed in the head chamber 10 an annular channel 22, from which leads an exhaust outlet 23 opening to atmosphere.

A reciprocatory valve is located in the valve casing 8, and preferably consists of two sections. This valve has terminal heads 24 and 25 that reciprocate in the respective head chambers 9 and 10. The head 24 therefore has a greater diameter than the head 25. Projecting from each head are reduced shank extensions 26 and 27 that operate in the bore 11 and abut against each other. The heads are hollow and are open-ended, and the shank 26—27 is provided with a bore 28 communicating with the hollow heads. As a consequence it will be evident that the head 24 has a peripheral end pressure surface 29 and an inset pressure surface section 30. The end of the head 24 is preferably provided with an inwardly extending annular flange 31, the inner surface 32 of which obviously equalizes the pressure on an equivalent portion of the surface 30. The inner end face 33 of the head 24 constitutes a pressure surface opposed to the pressure surfaces 29 and 30.

The head 25 similarly has an annular end pressure surface section 34 and an inset pressure surface 35. It is provided with an opposing pressure surface 36. Said head furthermore has an annular channel 37 forming a flange 38.

Extending into the outer ends of the head chambers 9 and 10 are plugs 39 and 40, against which the end faces 29 and 34 of the valve heads are respectively adapted to abut. The plug 39 is hollow and forms a supply port 41 leading from a throttle valve casing 42, in which is a suitable rotatable throttle valve 43.

The structure constitutes a differential valve, and its operation is substantially as follows: Referring first to Figure 2, the piston is at the rear end of its stroke, and the valve has been shifted to a forward posi-

tion. As a consequence it will be evident that the motive fluid entering through the port 41 of the plug 39 will pass behind the piston as the same returns from the end of its cushioned stroke, and drives said piston forwardly. During this forward drive the motive fluid in advance of the piston can exhaust freely through the ports 19 and 21, and by way of the head chamber 10 to the exhaust outlet 23. This is due to the fact that when the front end of the valve is abutted against the plug 40, the flange 38 is in an intermediate position with respect to the channel 22, so that both ports 19 and 21 are open to the exhaust outlet 23. During this stroke, the valve is held in its forward position by pressure against the rear end surfaces 29 and 30, which surfaces minus the surface 32, are sufficient to overcome the pressure against the opposite face 35 of the head 25, material pressure against the surface 34 being cut off by the contact of said surface against the end of the plug 40. The valve therefore remains in its forward position until the rear end of the piston 6 uncovers the port 14. When this occurs, additional pressure is brought against the surface 33 and the area of this surface plus the area of the surface 35 is sufficient to overcome the pressure against the surfaces 29 and 30, so that the valve is shifted to the position shown in Figure 1. When this occurs, the exhaust ports 19 and 21 are not only cut off by the piston 6, but the exhaust port 19 is cut off from the exhaust outlet 23 by the flange 38, while the exhaust port 21 is cut off by reason of the head 25 engaging the end wall of the channel 37. The rearward movement of the valve, however, opens port 14 in rear of the piston to the exhaust outlet 16, as shown. Therefore motive fluid passing through the valve and entering through the port 18 will drive the piston 6 rearwardly, while the exhaust can take place freely through the port 14, head chamber 9 and outlet 16. During this movement the valve will be held in its rearward position by reason of the fluid acting against the surfaces 34 and 35, the combined areas thereof being greater than the area of the surface 30 minus the opposing surface 32. As soon as the front end of the piston uncovers the port 19, then motive fluid in the front end of the piston chamber 5 will enter the inner end of the head chamber 10 and acting against the surface 36 cooperate with the surface 30 and shift the valve again forwardly or to the position shown in Figure 2. The above valve is found to have both speed and reliability, and it is so constructed that the five ports 13, 14, 19, 21, and 18 can be exceedingly short and of relatively large area. Moreover it will be noted that during the working stroke the exhaust in advance of the piston has a peculiarly

free means of exit, and even after the port 19 is closed by the advance of the piston, the exhaust can still take place through the port 21, so that a full forward stroke of the piston is obtained. It will be noted that the port 18 is not only short, but of large area, thus insuring a quick return movement of the piston, it being necessary however, that said port 18 be of materially less area than the bore 28, so that there is sufficient pressure in the short end of the head chamber 10 to insure the holding of the valve in its rear position during the rearward stroke. 70 75

From the foregoing, it is thought that the construction, operation and many advantages of the herein described invention will be apparent to those skilled in the art, without further description, and it will be understood that various changes in the size, shape, proportion and minor details of construction may be resorted to without departing from the spirit or sacrificing any of the advantages of the invention. 80 85

What I claim is:

1. In a fluid operated tool, a piston chamber, a piston therein, and a valve casing having chambers of different diameters, a valve in the casing having portions of different diameters operating in said chambers, and having a set of opposed pressure surfaces of substantially equal area, means for constantly supplying motive fluid to said chambers and against said opposing surfaces, ports opening from the valve casing chambers to the piston chamber and controlled by the valve, said valve having a second set of opposing pressure surfaces of unequal area, and trip ports from the piston chamber to the valve casing and controlled by the piston, said trip ports alternately supplying fluid from the piston chamber to the valve casing and against the surfaces of the second set for shifting the valve. 90 95 100 105

2. In a fluid operated tool, a piston chamber, a piston operating therein and a valve casing having head chambers of different diameters, a valve in the casing having heads of different diameters operating in said head chambers, said heads having one set of opposing pressure surfaces of substantially the same area and a second set of pressure surfaces that differ in area, supply ports opening from the head chambers to the piston chamber on opposite sides of the piston and controlled by the valve heads, means for supplying motive fluid to the head chambers for passage through the supply ports, said motive fluid having simultaneous access to the opposing pressure surfaces of substantially equal area, and trip ports between the piston chamber and the head chambers, said trip ports being covered and uncovered by the piston and alternately supplying motive fluid from the piston 110 115 120 125 130

chamber to the opposing pressure surface of different areas.

3. In a fluid operated tool, a piston chamber, a piston operating therein and a valve casing having head chambers of different diameters, a valve in the casing having heads of different diameters operating in said head chambers, said heads having a set of outer opposing pressure surfaces of substantially the same area and a second set of inner pressure surfaces that differ in area, supply ports opening from the head chambers to the piston chamber on opposite sides of the piston and controlled by the valve heads, means for supplying motive fluid to the outer ends of the head chambers for passage through the supply ports, said motive fluid having simultaneous access to the outer opposing pressure surfaces of substantially equal area, and trip ports between the piston chamber and the inner ends of the head chambers, said trip ports being covered and uncovered by the piston and alternately supplying motive fluid from the piston chamber to the inner opposing pressure surfaces of different areas.

4. In a fluid operated tool, a piston chamber and a valve casing having head chambers of different diameters, supply ports connecting the outer end portions of the head chambers and the outer end portions of the piston chamber, trip ports between the inner end portions of the head chambers and the corresponding portions of the piston chamber, a piston in the piston chamber, the ends of said piston respectively covering and uncovering the trip ports, a valve having heads of different diameters in the head chambers, said heads having inner surfaces acted on by motive fluid delivered to the inner ends of the head chambers through the trip ports when uncovered by the piston, and said valve heads each having outer surface sections whose combined area is greater than the said inner surface thereof, means for supplying motive fluid to the outer ends of the head chambers and against both outer surface sections of one head when the valve is in predetermined position, and means for cutting off the fluid in the outer end of the head chamber from access to one of the outer surface sections of the head thereof when the valve is in a shifted position.

5. In a fluid operated tool, a piston chamber and a valve casing having head chambers of different diameters, supply ports connecting the outer end portions of the head chambers and the outer end portions of the piston chamber, trip ports between the inner end portions of the head chambers and the corresponding portions of the piston chamber, a piston in the piston chamber, the ends of said piston respectively covering and uncovering the trip ports, a valve having heads of different diameters in the

head chambers, said heads having inner surfaces of different areas acted on by motive fluid delivered to the inner ends of the head chambers through the trip ports when uncovered by the piston and said valve heads each having outer surface sections whose combined area is greater than the said inner surface thereof, means for supplying motive fluid to the outer ends of the head chambers and against both outer surface sections of one head when the valve is in predetermined position, and stops against which the heads abut, said stops serving to cut off access of the fluid to certain of said outer surface sections.

6. In a fluid operated tool, a piston chamber, and a valve casing having head chambers of different diameters, supply ports connecting the outer end portions of the head chambers and the outer end portions of the piston chamber, trip ports between the inner end portions of the head chambers and the corresponding portions of the piston chamber, a piston in the piston chamber, the ends of said piston respectively covering and uncovering the trip ports, a valve having heads of different diameters in the head chambers, said heads having inner surfaces of different areas acted on by motive fluid delivered to the inner ends of the head chambers through trip ports when uncovered by the piston, and said valve heads having peripheral outer end surface sections of different areas and second outer surfaces inset from the peripheral surface and of substantially equal effective areas, means for supplying motive fluid constantly to the outer ends of both head chambers and against the inset surface sections of the heads, and abutments against which the peripheral surfaces alternately abut when the valve is shifted.

7. In a fluid operated tool, a piston chamber and a valve casing having head chambers of different diameters, supply ports connecting the outer end portions of the head chambers and the outer end portions of the piston chamber, trip ports between the inner end portions of the head chambers and the corresponding portions of the piston chamber, a piston in the piston chamber, the ends of said piston respectively covering and uncovering the trip ports, a valve having heads of different diameters in the head chambers, said heads having inner surfaces acted on alternately by motive fluid delivered to the inner ends of the head chambers through the trip ports when uncovered by the piston and said valve heads having outer surface sections whose combined area is greater than the said inner surfaces thereof, means for supplying motive fluid to one of the end chambers and against the outer end of the valve head therein, and a passageway

through the valve for directing motive fluid from said head chamber to the other outer end of the other head chamber and against the outer end of the valve head therein.

5. 8. In a fluid operated tool, a piston chamber and a valve casing having head chambers of different diameters, supply ports connecting the outer end portions of the head chambers and the outer end portions of the piston chamber, trip ports between the inner end portions of the head chambers and the corresponding portions of the piston chamber, a piston in the piston chamber, the ends of said piston respectively covering and uncovering the trip ports, a valve having heads of different diameters in the head chambers, said heads having inner surfaces alternately acted on by motive fluid delivered to the inner ends of the head chambers through the trip ports when uncovered by the piston and said valve head having outer surface sections whose combined area is greater than the said inner surfaces, means for supplying motive fluid to one of the end chambers and 25 against the outer end of the valve head therein, a passageway through the valve for directing fluid from said head chamber to the other outer end of the other head chamber and against the outer end of the valve 30 head therein, and abutments against which said valve heads alternately strike and cut off access of the fluid to portions of the outer surfaces of said heads.

9. In a fluid operated tool, a piston chamber and a valve casing having spaced head chambers of different diameters and a reduced bore connecting the head chambers, a piston in the piston chamber, supply ports between the outer portions of the head chambers and the piston chamber on opposite sides of the piston, trip ports between the inner portions of the head chambers and the corresponding portions of the piston chamber, said trip ports being covered and 40 uncovered by the piston, means for supplying motive fluid to the outer portion of one of the head chambers, a valve comprising heads in the head chamber provided with reduced shank extensions located in the bore, 45 said heads and shank extensions having a passageway therethrough affording communication between the outer ends of the head chambers and said heads controlling the supply ports, said heads furthermore having peripheral end surface sections of different 55 diameters and inset internal end surface sections of substantially the same effective areas operated on by the fluid in the head chambers, and surfaces against which the 60 peripheral surfaces alternately abut to cut off the access of fluid to said surfaces.

10. In a fluid operated tool, a piston chamber, and a valve casing having spaced head chambers of different diameters and a reduced bore connecting the head chambers,

a piston in the piston chamber, supply ports between the outer portions of the head chamber and the piston chamber on opposite sides of the piston, trip ports between the inner portions of the head chambers and the corresponding portions of the piston chamber, said trip ports being covered and uncovered by the piston, a valve comprising heads of different diameters in the head chambers provided with reduced shank extensions located in the bore and abutted, 70 said heads and shank extensions having a passageway therethrough affording communication between the outer ends of the head chambers, and said heads controlling the supply ports, said heads furthermore having peripheral end surface sections of different areas and inset internal end surface sections of substantially the same effective areas operated on by the fluid in the head chambers, 75 and closures for the outer ends of the head chambers and against which the peripheral ends of the heads abut, one of said closures having a passageway for the supply of motive fluid to the head chamber thereof and through the valve passageway to the other head chamber, the inner ends of the heads having faces of different areas that are alternately operated on by motive fluid admitted through the trip ports.

11. In a fluid operated tool, the combination with a piston chamber and a piston therein, of a valve casing having a chamber, spaced ports opening into the piston chamber and into the valve chamber, an exhaust outlet opening into the valve chamber at a point between the spaced ports, a valve having a head operating in the chamber and provided with a groove that is movable into and out of a position to afford communication between one of the ports and the exhaust outlets, and a flange that is correspondingly movable into and out of a position to afford communication between the other port and the exhaust outlet, said latter port being covered and uncovered by the piston.

12. In a fluid operated tool, the combination with a piston chamber and a piston therein, of a valve casing having a head chamber, a trip port between the inner end of the head chamber and the piston chamber, said trip port being covered and uncovered by the piston, an exhaust port between the piston chamber and head chamber and spaced from the trip port, an exhaust outlet opening into the head chamber in a line between the ports, an automatic valve in the valve casing having a head operating in the head chamber, said head having a channel movable to and from a position to afford communication between the exhaust port and the exhaust outlet, and said valve having a flange movable to and from a position between the trip port and exhaust outlet

and in a position to be operated against by fluid admitted through the trip port when said trip port is uncovered by the piston, and means for stopping the valve when moved in one direction with the channel and flange in positions to cut off the exhaust outlet from the ports, and stopping the valve when moved in the opposite direction in a position to open both ports to the exhaust outlet.

10 13. In a fluid operated tool, the combination with a piston chamber and a piston therein, of a valve casing having head chambers, a valve having heads that reciprocate in said chambers, said chambers having ports communicating with the piston chamber on opposite sides of the piston and being controlled by the valve, means for supplying motive fluid to one of the head chambers, a passageway through the valve for conducting motive fluid from said head chamber to the other chamber for supplying motive fluid to the piston chamber through the port thereof, said passageway having greater capacity than said port, opposing pressure surfaces on the valve heads that are acted on by the motive fluid in said head chambers, said valve having other opposing pressure surfaces, and means controlled by the piston for alternately delivering fluid under pressure against said other opposing pressure surfaces.

35 In testimony whereof, I affix my signature.
